SOLAR COMPASS

Ernest D. Bean, Plattsburg, N. Y.

Application January 16, 1935, Serial No. 1,256

5 Claims. (Cl. 33—62)

This invention relates to a solar compass for determining direction through the instrumentality of an indicator mechanically rotated at uniform rate through a circular arc in a specific time interval which in certain embodiments of the invention may be twenty-four hours and in others twelve hours.

The invention therefore finds its logical embodiment in combination with a timepiece such as a watch or clock.

Figure 9 is a vertical section through the device shown in Figure 8.

Referring now in detail to the several figures and first advertizing to that form of the invention shown in Figure 1, the numeral 1 represents in general a timepiece having the dial 2, minute hand 3 and hour hand 4. The minute hand is of no particular value in carrying out the operation of the present invention and is only shown as being part of the conventional timepiece. A device in which the hour hand alone is provided would operate equally well. The dial is provided with the conventional set of hour numerals from 1 to 12, circumferentially arranged. The device operates upon the well known principle that when the hour stand is directed to the sun, the line representing the north and south direction will always bisect the angle between the hour hand and the hour numeral 12.

In carrying out this principle, two arcuate series 5 and 6 of numerals are provided which for convenience are arranged in concentric relation to the rotational center of the hour hand, respectively outside and inside of the series of time numerals. These arcuate series of auxiliary numerical characters do not rotate, but are fixed upon the dial of the timepiece and are designated respectively by words indicating "Afternoon north points" and "forenoon north points". The auxiliary numerical characters are such and so arranged that with the timepiece reading correct time and with the hour hand directed at the sun, during the afternoon, the particular numeral of the afternoon series found in line with the hour hand, indicates the point on the hour numeral circumference which determines a radius from the rotational center of the timepiece, pointing north.

In a similar manner, whenever the hour hand is directed to the sun during forenoon time, the corresponding north point can be similarly determined by using instead the numerals found on the inner or forenoon series 6. For example, in Figure 1, supposing the sun is in line with the hour hand. The numeral 4½ found at the point of the hour hand indicates that a radius from the center of the timepiece through the quarter to five point on the hour circle will be pointing north.

It will be observed that for the sake of clarity and the avoidance of confusion, the series of auxiliary numerical characters are continued only through such range as would be useful in locations where the sun rises as early as 3 a. m. and sets as late as 9 p. m. These ranges may be curtailed or extended according to the exigencies of use.

In the dial 7 illustrated in Figure 2 and which is designed for the Southern Hemisphere, the forenoon and afternoon auxiliary numerical

5. Another object of the invention is the provision in a device of the character described, of means for indicating time and direction without recourse to magnetism, and without interfering with the normal operation of the timepiece.

20. A further object of the invention is to provide in a timepiece compass, a non-magnetic direction indicator arranged to avoid uncertainty as to whether the indicating device is pointing north or diametrically opposite, and to prevent reliance upon such spurious indication of direction as would arise should the timepiece have been inaccurately set.

Still another object of the invention is to provide a solar compass of the class described in combination with correlated indicia on a boat, ship, aircraft, land or any other vehicle, by which the course of the same, or variations in the course, may be ascertained, and thereby new courses may be laid.

35. Other objects of the invention will appear as the following description of preferred and practical embodiments thereof proceeds.

In the drawings which accompany and form a part of the following specification and throughout the several figures of which the same characters of reference have been employed to designate identical parts:

Figure 1 is a plan view of a timepiece exemplifying one embodiment of the invention;

45. Figure 2 is a plan view of the same timepiece with the dial arranged for observations in the Southern Hemisphere;

Figure 3 is a plan view of a modified form of the invention;

50. Figure 4 is a detail in perspective of the hour hand employed in that form of the invention shown in Figure 3;

Figure 5 is still another modified form of the invention;

55. Figure 6 is a plan view of an adaptation of my invention to a boat compass;

Figure 7 is a vertical section through that form of the invention shown in Figure 6;

60. Figure 8 is a plan view similar to that of Fig. 6, showing another form of the invention; and

characters are such and are so arranged as to conform with conditions obtaining in the Southern Hemisphere.

In that form of the invention illustrated in Figure 3, the timepiece 8 comprises a dial 9 having the conventional hour circle 10 with figures from 1 to 12, inclusive. The face of the dial and the hour hand 11 are provided with complementary curves 12 and 13, respectively. The curve 12 being fixed with respect to the dial, may be painted thereupon or applied thereto in any suitable manner. The curve 13 being carried rotationally by the hour hand 11, is necessarily of relatively rigid character and may be integral 15 with the hand itself or suitably attached thereto. The point 14 of apparent intersection of the curves 12 and 13 shifts with the rotation of the hour hand and a line from the center of rotation of the hour hand through said shifting point 20 14 indicates the direction north, when the hour hand is pointed at the apparent sun.

The curves in the illustration are represented as spirals, but are not necessarily such, since other intersecting curves may be plotted that 25 will give the same shifting apparent intersection. However, at every point of intersection, the spiral curves as shown intersect at the widest possible angles, therefore more definitely determining the point of their apparent intersection.

30 The outer extremity of the fixed curve is preferably located on a radial line which passes through the time numeral 1:30 o'clock, and the inner end of this curve is on a radius passing through the time numeral 10:30 o'clock. A point 35 15 on this same curve, determined by the intersection of a radius passing through the hour numeral 6, separates the curve into afternoon and forenoon sections 17 and 18, respectively, the former including the inner portion of said curve 40 and being preferably colored dark, while the forenoon section constituting the outer part of said curve is colored light.

45 The curve carried by the hour hand is similar, but opposite in its arrangement to the fixed curve. It is somewhat longer at its inner end than the fixed curve to permit its attachment to the hour hand. The point 16 which is exactly the same distance from the outer extremity of the 50 movable curve as the point 15 is from the corresponding end of the fixed curve, divides the movable curve into inner and outer sections representing respectively ranges of afternoon and forenoon positions of the shifting point of intersection 14, and being contrastingly colored. The 55 outer end of the movable curve has an extension 22 which is mere brace and is preferably so colored as to be unobtrusive.

60 The third form of the invention, illustrated in Figure 5, relates to a timepiece having the usual time hands 23 and 24 and a third hand or direction indicator 25, the latter hand being mounted on an arbor geared to operate at half speed with respect to the arbor which actuates the hour hand 23, and therefore carrying out the principle 65 of the invention above enunciated by always indicating the bisector of the angle between the hour numeral 12, when the clock is keeping correct time and is positioned so that the hour hand points at the sun. In order for the invention in this form to function as a direction indicator, it is essential at the time of first setting the device and every time it is set thereafter after having stopped, that the hands be so set that the time hands are together at the hour numeral 12 and the direction indicating hand 25 is simultaneously

pointing at the hour numeral 6, if setting is done during the afternoon but if setting is done during the forenoon, that the hands be so set that the time hands and the direction indicating hand are all simultaneously pointing at the hour numeral 12, after which setting in either case the hands must be rotated in a clockwise direction to proper time.

5 The hand 25 preferably displays the letters N and S at its opposite ends, N being at the indicating point thereof and it preferably bears also the letters E and W in a line perpendicular to the shaft of the hand, the letter E being displayed on the clockwise side of the hand and the letter W on the opposite side. The third hand 25 geared at half speed with respect to the hour hand is all that is absolutely essential to make this a complete operative device. It is merely necessary to bodily turn the instrument, with the face 10 up until the hour hand points to the sun and the third hand will point in a direction north. However, this is only the case if the timepiece has been originally set with the hands in the relation above stated.

15 If the timepiece had been set with the hands 25 in reversed relation, that is to say, all three hands on the hour numeral 12, when the time hands should have been on the hour numeral 12 and the indicator hand 25 on the hour numeral 6, this will not be the case for while the 20 third hand will lie in a north and south line when the hour hand is pointing to the sun, the north end of the third hand will be pointing south. Therefore, to avoid confusion and to assure the observer that the timepiece was set 25 correctly and is therefore not giving him a spurious indication of direction, it is desirable to arrange a series of "Afternoon north points" 26 and "Forenoon north points" 27 in encompassing relation to the dial respectively outside and 30 inside of the hour numerals and concentric with the rotational center of the hands of the timepiece. The afternoon and forenoon north points 35 are so numeralized with respect to the hour numerals, that with the timepiece running and indicating correct time, and the hour hand 23 directed at the sun during the afternoon, the numeral in the "Afternoon north point" column immediately in line with the hour hand indicates the hour numeral determining a radius from the 40 rotational center of the timepiece directed northwardly, and toward which the pointing end of the hand 25 is directed if the hands have been correctly set. Likewise, when the hour hand is directed to the sun during forenoon time the numerical character then occurring in the series of "forenoon north points" 45 adjacent to the point of the hour hand similarly shows what time point in the series of hour numerals is at that instant simultaneously north. It is obvious, with this 50 combined timepiece and solar compass, that the presence of the series of afternoon and forenoon points acts as a check upon the accuracy of the indication of the direction hand 25, for if at any observation, the afternoon or north point numeral at the extremity of the hour hand does not correspond to the hour numeral simultaneously at the point of the third hand, it is at once known that the original setting of the timepiece was not correctly done and that the direction hand 55 is pointing south instead of north.

55 The range of afternoon and forenoon north point numerals is exemplary only and a greater or less number of daylight hours may be provided for by either diminishing or extending the 60 65 70 75

The range of afternoon and forenoon north point numerals is exemplary only and a greater or less number of daylight hours may be provided for by either diminishing or extending the 75

range of said afternoon and forenoon north points according to convenience or necessity.

Any one of the three forms of the invention above described is adapted to be employed as an indicator of direction or in determining courses in the movement of land, water or air vehicles. Figures 6 to 9 illustrate the third form of the invention, that is to say, the solar compass provided with an indicating hand employed as a direction indicator on a boat. In Figure 6, the bow of the boat is represented at 28 on which is suitably mounted a turntable 29 of suitable diameter to suit the solar compass. Outside of the turntable and in fixed relation to the boat is an annulus 30 showing the cardinal points N. E. S. and W. and the degree angles therebetween. The west point is on the right with the east point diametrically opposite. The north and south points are coincident with the lubber line 31. In determining the direction in which the boat is moving, the solar compass is placed on the turntable and the latter rotated until the hour hand 23 points to the sun. The third or direction indicating hand 25 points to north and in the example shown, it is obvious that the lubber line of the boat is directed 60° east of north.

Another and perhaps a more convenient arrangement is shown in Figure 8 in which the turntable 29 is surrounded by a revolvable annulus 32 carrying the cardinal points N. E. S. W. and the intermediate angles in terms of degrees. In this form of the invention the east and west marks are in their natural positions, east being to the right of north. The annulus 32 revolves with respect to the fixed lubber line 31. The solar compass is placed upon the turntable and the latter oriented until the hour hand 23 points to the sun. The third hand is then pointing north. The annulus 32 is then revolved until the cardinal point north coincides with the line of direction of the third hand 25, whereupon the point on the annulus intersected by the lubber line indicates the course of the vessel.

As stated, any other of the described forms of solar compass may be substituted for that form of the invention herein shown upon the turntable.

It is to be understood that while I have in the foregoing disclosure described what I believe to be preferred and practical forms of the invention, these are merely by way of illustration and not to be construed as limiting the invention which may find legitimate embodiment in many other mechanical constructions and arrangements which may be considered the equivalent of those herein illustrated and described.

What I claim is:

1. Solar compass comprising a dial and an hour hand mechanically rotated at uniform speed through one revolution in twelve hours, said dial having an annular scale of hour indices, said hour hand and said dial being provided with cooperating linear index members similar throughout their working ranges and reversely placed in intersecting relation whereby the point of intersection shifts with the revolution of said hour hand, said linear indices being so shaped and disposed that when the compass is oriented to a position in which the hour hand, keeping correct time, points 60 at the sun, said point of intersection lies north-

erly with respect to the rotational axis of the hour hand.

2. Solar compass comprising a dial and an hour hand mechanically rotated at uniform speed through one revolution in twelve hours, said dial having an annular scale of hour indices, said hour hand being provided with a curved member and said dial displaying a cooperating curve similar to the curvature of said curved member throughout the working range of said curves, but reversely placed in intersecting relation, said curves being extended sufficiently around the rotational center of said hour hand to provide two points of intersection for at least part of the time, said points of intersection shifting with the revolution of said hour hand, said linear indices being so shaped and disposed that when the compass is oriented to a position in which the hour hand, keeping correct time, points at the sun, one of said points of intersection lies north- 10 erly with respect to the rotational axis of the hour hand, the ranges of movement of said intersecting points on said curves being contrastingly distinguished respectively for forenoon and after- 15 noon observations.

3. Solar compass comprising a dial and an hour hand mechanically rotated at uniform speed through one revolution in twelve hours, said dial having an annular scale of hour indices, said hour hand being provided with a spirally curved member and said dial displaying a cooperating curve similar to the curvature of said curved member throughout the working range of said curves, but reversely placed in intersecting relation, said curves being extended sufficiently 30 around the rotational center of said hour hand to provide two points of intersection for at least part of the time, said points of intersection shifting with the revolution of said hour hand, said curves being so shaped and disposed that when 35 the compass is oriented to a position in which the hour hand, keeping correct time, points at the sun, one of said points of intersection lies north- 40 erly with respect to the rotational axis of the hour hand, the ranges of movement of said intersecting points on said curves being contrastingly distinguished respectively for forenoon and after- 45 noon observations.

4. Solar compass comprising a dial having an annular scale of hour indices, and an hour hand 50 cooperating with said scale, an additional hand mechanically rotated at half the speed of said hour hand and in such relationship thereto that when the compass is oriented so that the hour hand, keeping correct time, points at the sun, 55 the additional hand simultaneously points north-erly.

5. Solar compass comprising a dial and an hour hand mechanically rotated at uniform speed through one revolution in twelve hours, said dial 60 having an annular scale of hour indices, means moving relative to said dial and moving in a definite relation to the motion of said hour hand, for determining a point on said dial, which point together with the axis of rotation of said hour 65 hand determines a north and south line when the compass is oriented to a position in which the hour hand, keeping correct time, points to the sun.
